UNITED STATES PATENT OFFICE.

FAY OSCAR FARWELL, OF DUBUQUE, IOWA, ASSIGNOR OF ONE-HALF TO
THE ADAMS COMPANY, OF SAME PLACE.

DESIGN FOR A CASING FOR INCLINOMETERS.

SPECIFICATION forming part of Design No. 34,017, dated January 29, 1901.

Application filed November 16, 1900. Serial No. 36,779. Term of patent 14 years.

To all whom it may concern:

Be it known that I, FAY OSCAR FARWELL, a citizen of the United States, residing at Dubuque, in the county of Dubuque and State of Iowa, have invented and produced a new and useful Design for a Casing for Inclinometers; and I do hereby declare the following to be a full, clear, and exact description of the invention, such as will enable others skilled in the art to which it appertains to make and use the same.

The invention or production is illustrated in the accompanying drawing, where an instrument of this character that is shaped and ornamented in accordance with my design is shown in perspective.

As illustrated in the drawing, the leading or material feature of the design consists in the shape of the instrument, which, as shown, is formed longitudinally on the curve of a long rather flat arc, and has the central part

of its top cut out in the form of a long narrow slot *b*, leaving an opening through which one may look down from above, and which has its ends extended beyond the slot in the general direction of the chord of the arc on which said body part is struck. On one side of the slot *b* the top surface of the instrument is provided with a series of graduations, as shown.

Having thus described my invention, what I claim, and desire to secure by Letters Patent, is—

The design for a casing for inclinometers substantially as herein illustrated and described.

In testimony whereof I affix my signature in presence of two witnesses.

FAY OSCAR FARWELL.
